CLAIM

The ornamental design for an interlocking toy brick as shown and described.

DESCRIPTION

FIG. 1 is a front perspective view of an interlocking toy brick.

FIG. 2 is a top perspective view of the interlocking toy brick.

FIG. 3 is a top view of the interlocking toy brick.

FIG. 4 is a bottom view of the interlocking toy brick.

FIG. 5 is a side view of the interlocking toy brick.

FIG. 6 is an end view of the interlocking toy brick.

FIG. 7 is a bottom perspective view of the interlocking toy brick.

FIG. 8 is a front perspective view of a second embodiment of the interlocking toy brick.

FIG. 9 is a top perspective view of the second embodiment of the interlocking toy brick.

FIG. 10 is a top view of the second embodiment of the interlocking toy brick.

FIG. 11 is a bottom view of the second embodiment of the interlocking toy brick.

FIG. 12 is a side view of the second embodiment of the interlocking toy brick.

FIG. 13 is an end view of the second embodiment of the interlocking toy brick; and,

FIG. 14 is a bottom perspective view of the second embodiment of the interlocking toy brick.

The broken lines in the figures show features of the interlocking toy brick that form no part of the claimed design.
